DENTAL CARE CABINET

Margaret C. Osburn, 22801 Shakespeare,
East Detroit, Mich. 48021

Filed May 27, 1965, Ser. No. 85,484

Term of patent 14 years

(Cl. D4—3)

FIG. 1 is a perspective view of a dental care cabinet embodying my design;

FIG. 2 is a perspective view thereof with the sliding cover removed;

FIG. 3 is a front elevational view thereof with the sliding cover removed;

FIGS. 4, 5 and 6 are, respectively, side, top and bottom elevational views thereof;

FIGS. 7 and 8 are sectional views of my design taken, respectively, along the line 7—7 and 8—8 of FIG. 1; and

FIG. 9 is a fragmentary view in elevation taken along the line 9—9 of FIG. 7.

The toothbrush, dentifrice tube and mounting screws are shown for illustrative purposes.

I claim:

The ornamental design for a dental care cabinet, as shown and described.
